UNITED STATES PATENT OFFICE.

LEONARD B. BUCHANAN, OF WOBURN, MASSACHUSETTS, ASSIGNOR TO CHASE-SHAWMUT COMPANY, OF NEWBURYPORT, MASSACHUSETTS, A CORPORATION OF MAINE.

INCLOSED ELECTRIC FUSE.

1,033,754.

Specification of Letters Patent.

Patented July 23, 1912.

Application filed January 11, 1910. Serial No. 537,391.

To all whom it may concern:

Be it known that I, LEONARD B. BUCHANAN, of Woburn, county of Middlesex, and State of Massachusetts, have invented an 5 Improvement in Inclosed Electric Fuses, of which the following is a specification.

This invention relates to electric-fuses, and particularly to fuses of the inclosed type, having means for indicating when the 10 fuse is blown.

The invention consists in making a part or the whole of the fuse-case of glass, mica, cellulose acetate, or other substance through which the color of the material in the case 15 may be seen, and placing within the case, close to a transparent part thereof, a material which will undergo a chemical change when the fuse blows, resulting in a change of color by reason of the chemical action 20 upon it of gases formed within the fuse-case on the fusion of the fusible element, such gases being formed from the filler under the influence of the electric-current and the metal vapor of the fusible element. Other 25 indicating-devices have been proposed in which a part outside the wall of the fuse-case is burned, charred or burst by the heat or expansion of the gases in the case, but such devices are open to the objection that 30 the fire outside the fuse-case may ignite surrounding material, and, unless there is a burning heat outside the case, the device does not operate, and in general any device involving an opening in the side wall of the 35 fuse-case is dangerous as permitting the escape of burning gases on short circuit. These objections have been met to a considerable extent in devices now used, but extreme care in construction is required, and, 40 in spite of extreme precaution, dangerous flames and annoying failures to indicate still occur.

Among the advantages of my device is the elimination of the opening in the side wall 45 of the fuse-case through which flame may escape, and the elimination of shunt or other auxiliary wires or connections requiring delicate adjustment and complicating the operation of assembling and filling the fuse. 50 Moreover, since in my device the color change of the indicating means is effected by a chemical reaction, as distinguished from burning, charring, melting, or bursting, the change of color will take place at the fuse-

case wall, at any temperature or pressure, 55 and the use of explosives at the fuse-case wall, to produce the requisite heat or pressure required in many devices now used, is avoided.

Figure 1 is a plan view of an inclosed 60 electric-fuse embodying this invention before the fuse has blown, Fig. 2 is a similar view after the fuse has blown, Fig. 3 is a longitudinal vertical section of the fuse shown in Fig. 1, Fig. 4 is a longitudinal 65 vertical section of a modified form of fuse, the fuse-case being composed in part of transparent material, and an indicating material applied to the interior of the transparent part thereof, Fig. 5 is a similar 70 longitudinal vertical section of the fuse shown in Fig. 4, the indicating material being mixed with the filler.

In practising my invention it is for many reasons desirable to employ as a fuse-case a 75 tube *a* of mica or cellulose acetate closed at the ends with metal caps *a'*, see Figs. 1 and 2, but, owing to the expense, this is not always practicable, and it is sufficient if the fuse-case be composed principally of fiber, 80 closed at the ends with metal caps, a part of the wall, as *d*, of which is made of mica, glass, cellulose acetate, or other reasonably transparent material of sufficient strength and pressure-and-heat-resisting qualities. 85 With this exception the ordinary construction of the fuse with metal end-caps and zinc or other metal-fuse-strip *b* may be used. In both instances, it will be observed, a fuse-case is produced which is devoid of a side 90 opening through which flame may escape. In said fuse-case, and around the fuse-strip *b*, an arc-smothering material or filler *c* is placed; and also in said case an indicating material *c'* is placed, the color of which is 95 adapted to be changed by chemical reaction.

In practising my invention it is important to use as or in connection with the arc-smothering material *c* a substance releasing some gas, non-condensing at ordinary temperatures, which will spread through the fuse-case after the fuse has blown and metathetically react upon the indicating material *c'* and change its color. Plaster of Paris, set or unset, is well suited for this 100 purpose, as H_2S and other sulfur-bearing gases are liberated from this, when the fuse 105 blows, by the action of the hot metal vapor

of the fuse-strip on the plaster of Paris 5
filler under the influence of the electric current. Other substances may be mixed with this to increase the amount of H_2S given off
on slight overload under mild conditions,
for instance, iron pyrites. In such cases
the additional substances should preferably
be near the fusing point of the strip, but
such substances are merely auxiliary and
are not necessarily included in my invention.
10

As is well known to chemists, sulfureted
hydrogen and other sulfur-bearing gases,
will react metathetically upon many well-
known substances to change their color, and
15 some such substance, stable under ordinary
conditions, should be chosen as the indicating
material. Lead compounds, particularly the acetate and carbonate, or the lead
oxid minium, are, perhaps, the most common
20 and simplest of these to use. Acetate or
carbonate of lead are white substances
which react with sulfureted hydrogen metathetically
to form sulfid of lead, a black
substance. A further advantage of the
25 use of acetate or carbonate of lead is
that the zinc vapor formed when the fuse
blows may assist the effect by reacting
metathetically upon it to form a black com-
pound, but this is unreliable on slight over-
30 load and is not the principle on which my
indicator operates in practice. The indicating
material may be colored by red oxid
of lead, or other suitable coloring matter,
to give any color distinct from black with-
35 out departing from my invention, which
covers any contrasting colors.

I prefer to apply the indicating material
c' by washing the transparent part *d* of the
fuse-case with it, see Fig. 4, but another
40 simple way is to mix a small amount of it
with the filler *c*, see Fig. 5, in which case
sufficient of it will be next to the transparent
part to furnish the required indication. In
either case, until the fuse is blown the indi-
45 cating material shows through the trans-
parent portion of the fuse-case, and the ob-
server may determine from its color whether
the fuse has blown or not.

It is obvious that almost any substance
50 changing in color by the action of H_2S may
be used as an indicating material without
departing from my invention.

I claim:

1. An inclosed electric-fuse of the car-
55 tridge type, having an exterior non-conduct-
ing tube with metal end-caps, said tube hav-
ing a transparent portion, lead acetate with-
in the casing, visible through said trans-
parent portion, a fusible metal current-con-
60 ducting element within the tube, and finely
divided plaster of Paris within the tube sur-
rounding the fusible element, substantially
as described.

2. An inclosed electric-fuse of the car-
65 tridge type, having an exterior non-conduct-

ing tube with metal end-caps, said tube hav-
ing a transparent portion, a lead compound
characterized by forming a sulfid on con-
tact with sulfureted hydrogen, substantially
as described. 70

3. An inclosed electric-fuse of the car-
tridge type, having an exterior non-conduct-
ing tube with metal end-caps, said tube hav-
ing a transparent portion, a compound
characterized by forming a sulfid on contact 75
with sulfureted hydrogen, and a filler which
when acted upon chemically by the vapors
of the fusible metal will produce sulfureted
hydrogen, substantially as described. 80

4. An inclosed electric-fuse of the car-
tridge type, having a fuse-case with a trans-
parent portion, a fusible metal current-con-
ducting element within the case, plaster of
Paris within the case surrounding the fusible
85 element, an indicating material within
the case, visible through said transparent
portion which will change in color when
acted upon by the gases formed from the
plaster of Paris upon the blowing of the
90 fuse. 85

5. An inclosed electric-fuse having a fuse-
case with a transparent portion and contain-
ing a metallic fusible element, a filler con-
tained in said case and indicating material
other than said filler also contained in said
95 case, visible through said transparent por-
tion, which is adapted to be changed by
chemical reaction produced by a gas formed
from the filler upon blowing of the fuse, re-
sulting in a change in color, substantially
100 as described. 95

6. An inclosed electric-fuse having a fuse-
case with a transparent portion and contain-
ing a metallic fusible element, indicating
material contained in said case and visible
105 through the transparent portion thereof, and
a filler also contained in said case containing
a substance which reacts upon the indicating
material when the fuse blows to produce a
change in color of said indicating material,
110 substantially as described. 105

7. An inclosed electric-fuse having a fuse-
case with a transparent portion and contain-
ing a metallic fusible element, indicating
material contained in said case and visible
115 through the transparent portion thereof, and
a filler also contained in said case, said fusible
element and filler forming gases, when
the fuse blows, which react upon the indi-
cating material and change its color, sub-
stantially as described. 120

8. An inclosed electric-fuse of the car-
tridge type, having a fusible element with-
in the casing and an arc-smothering filling
material surrounding the fusible element
125 which when acted upon chemically by the
vapors of the fusible metal will cause an in-
dication of the blowing of the fuse, visible
from outside the fuse, consisting in a chemi-
cal change of an indicating material distinct
130

from the arc-smothering material, substantially as described.

9. An inclosed electric-fuse of the cartridge type, composed of a cylinder having a non-conducting side with a transparent portion and metal end-caps, lead acetate within the casing, visible through said transparent portion, a fusible current-conducting element of metal within the casing, and a filling material of finely divided plaster of

Paris within the casing surrounding the fusible element, substantially as described.

In testimony whereof, I have signed my name to this specification, in the presence of two subscribing witnesses.
